UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK.

PROTECTIVE DEVICE.

1,099,590.

Specification of Letters Patent. Patented June 9, 1914.

Application filed July 13, 1907. Serial No. 383,636.

To all whom it may concern:

Be it known that I, ELMER E. F. CREIGHTON, a citizen of the United States, residing at Schenectady, county of Schenectady, 5 State of New York, have invented certain new and useful Improvements in Protective Devices, of which the following is a specification.

My invention relates to protective devices 10 for electric conductors and more particularly to devices which establish a conducting path between the conductor and ground during the continuance of abnormal voltage on the conductor.

15 A common type of protective device comprises a connection between the conductor and ground in series with two electrodes separated by air or other dielectric to form a spark gap which will break down upon 20 the occurrence on the conductor of voltages beyond a predetermined limit. In an arrangement of this type the gap between the electrodes breaks down almost instantly and establishes a conducting path to ground 25 upon the occurrence on the conductor of a steady abnormal voltage or of oscillations of abnormal voltage and certain frequency. If oscillations of the same voltage but of 30 different, and particularly of higher frequency occur, a considerable period of time elapses before the dielectric between the electrodes breaks down, and during this time part of the high frequency oscillations may 35 go to ground through the translating devices, but if inductance is placed in series with the spark gap to ground the time lag exhibited by the spark gap in the presence of high 40 frequency oscillations is practically eliminated and the spark gap will break down almost instantly when very high frequency 45 oscillations occur upon the conductor. Experiments have demonstrated that oscillations of extremely high frequency encounter more difficulty in breaking down an air gap 50 than the oscillations of lower frequency produced by passing the extremely high frequency oscillations through inductances connected in series with the air gap. If two 55 gaps are connected in parallel, one having an inductance in series and the other having no inductance and both are subjected to oscillations of the same high frequency, the gap in series with the inductance may be made more than twice as great as the gap without inductance and yet the discharge

will always take place at the gap having inductance in series.

It has been proposed to relieve the conductor of very high frequency oscillations by using a number of spark gaps in parallel, one having no inductance and the others having inductance in series therewith, but this is an ineffective arrangement, because when very high frequency oscillations appear upon the conductor the spark gap with no inductance does not break down quickly enough and while the other gaps break down almost instantly they do not permit free discharge after they have broken down.

60 The object of my invention is to provide a protective device between the conductor and ground arranged to act almost instantly upon the appearance of a voltage beyond a predetermined limit, regardless of the frequency of the oscillations of voltage, and establish a direct non-inductive conducting connection to ground to permit free discharge to relieve the conductor.

65 In carrying out my invention I connect the conductor to ground through two main electrodes separated by a spark gap or similar arrangement and provide a means co-operating with the spark gap and responsive to high frequency oscillations for ionizing and 70 causing the break down of the dielectric between the main electrodes thereby forming a direct non-inductive path to ground. The means which I prefer to employ for this purpose comprises an auxiliary electrode 75 connected to the conductor through a resistance or similar device for introducing inductance into the circuit and so arranged that when high frequency oscillations occur 80 upon the conductor, a discharge instantly passes to ground from the auxiliary electrode, ionizing and puncturing the dielectric between the main electrodes and thereby 85 instantly establishing a conducting path to ground to relieve the conductor of abnormal voltage.

90 Other devices may be substituted for the air gap and other means responsive to high frequency oscillations may be substituted for the electrode connected through an inductance.

95 My invention will best be understood in connection with the accompanying drawings which are merely an illustration of one embodiment of my invention and in which—

100 Figure 1 is a diagrammatic view of a con-

105

110

ductor provided with a protective device embodying my invention; and Fig. 2 is a view of the device shown in Fig. 1 with part thereof omitted for the sake of clearness.

In the drawings the conductor or line wire 1, which is to be protected, is connected through a reactance 2 or similar device to the translating device 3 which may be a transformer, a generator, a motor, or similar device. The conductor 1 is connected to ground through an electrode 4 separated from a coöperating grounded electrode 5 by a spark gap, which breaks down when an abnormal voltage occurs upon the conductor 1 and establishes a direct non-inductive circuit between the conductor 1 and ground through the electrode 4, the spark gap, and the electrode 5, and instantly relieves the conductor 1 of the abnormal voltage.

If a very high frequency oscillation occurs upon the conductor 1, the gap between the main electrodes 4 and 5 exhibits a pronounced time lag and requires such a length of time to break down that the insulation on the translating devices may be punctured, and in order to avoid this danger I provide means responsive to high frequency oscillations for causing the gap between the main electrodes 4 and 5 to break down instantly. The device which I prefer to use for this purpose comprises an auxiliary electrode 6, connected to the conductor 1 and having an inductance 10 in series therewith and so arranged that high frequency oscillations on the conductor 1 will instantly cause a discharge from the electrode 6 through the dielectric between the electrodes 4 and 5, thereby ionizing and puncturing the dielectric and establishing a direct non-inductive path between the conductor 1 and the ground. It seems that the amount of the inductance between the electrode 6 and the conductor 1 determines the frequency of the oscillations which will instantly cause a discharge from the electrode, and in order to insure the breaking down of the dielectric between the main electrodes 4 and 5, by oscillations of any frequency, I provide any desired number of auxiliary electrodes, 6, 7, 8 and 9 connected to the conductor in series with inductances 10, 11, 12 and 13, differing from each other in amount and proportioned to respond to oscillations of varying frequency, so that for instance oscillations of one frequency will cause a discharge through electrode 6, of another frequency will cause a discharge through electrode 7, and of still another frequency will cause a discharge through electrode 8.

The auxiliary electrodes are arranged to insure that any discharge to ground from them will necessarily pass through the dielectric between the main electrodes 4 and 5 to establish a direct non-inductive path be-

tween the conductor and ground, and the preferred arrangement is shown in Fig. 2 in which the electrodes 6 and 8 are separated from the main electrode 4 by a very small air gap and are so positioned with relation to the electrode 4 that a discharge from either electrode 6 or 8 will go to the main electrode 4 and thence through the air gap to the main electrode 5, and thence to ground.

In order to prevent the dynamo current forming an arc across the gap between the electrodes 4 and 5, any suitable current limiting device, preferably an aluminum cell 14, containing aluminum electrodes immersed in a suitable electrolyte, is connected between the electrode 5 and the ground. My invention renders the spark gap very sensitive to a great variety of abnormal conditions on the conductor, and instantly relieves the conductor through the device 14 to ground without the formation of a destructive arc, so that the usefulness of lightning arresters consisting of a spark gap in series with a current limiting device is very greatly extended.

My invention may be embodied in many other forms than that shown and described; I therefore do not desire to be restricted to the precise arrangement shown and aim to cover by the appended claims all changes and modifications within the spirit and scope of my invention.

What I claim as new and desire to secure by Letters Patent of the United States, is,—

1. In a protective device for electric conductors, the combination of a non-inductive low resistance discharge path to ground, responsive to definite abnormal conditions on said conductor, and means comprising a plurality of circuits of differing inductance responsive to a wide range of other abnormal conditions for causing said discharge path to break down.

2. In a protective device for electric conductors, the combination of a non-inductive discharge path containing a spark gap, a plurality of inductive devices containing different amounts of inductance, and auxiliary spark gaps connected in series with said devices to respond to high frequency oscillations in said conductor, said inductances being connected in parallel to said conductor and said auxiliary spark gaps being mounted to coöperate with the spark gap of said discharge path to cause said spark gap to break down.

3. In a protective device for electric conductors, the combination of a non-inductive discharge path containing a spark gap and responsive to definite conditions on said conductor, and a plurality of helices connected to said conductor in parallel with one another, said helices forming with said spark gap a plurality of circuits differently ef-

fected by high frequency oscillations and responding to different conditions on said conductor to cause said spark gap to break down, whereby said discharge path is rendered sensitive to a wide range of abnormal conditions on said conductor.

4. In a protective device for electric conductors, the combination of a main discharge path containing main electrodes separated by a spark gap, and a plurality of auxiliary electrodes spaced away from said main electrodes to form auxiliary spark gaps which discharge to one of said main electrodes and thereby cause said main spark gap to break down, said auxiliary electrodes being connected to said conductor through inductive coils which render the circuits through the auxiliary electrodes responsive to high frequency oscillations and which differ from each other in amount, each of said inductive coils having inductance greater than the inductance of said main discharge path.

5. In a protective device for electric conductors, the combination with a main electrode connected to the conductor and arranged to form a non-inductive path to ground during a discharge from said electrode, of an auxiliary electrode having inductance in series therewith connected to said conductor and spaced away from said main electrode to form an auxiliary spark gap in a circuit which is responsive to high

frequency oscillations and discharges through said auxiliary gap to ground through said first electrode.

6. In a protective device for electric conductors, the combination with a main electrode connected to the conductor and arranged to provide a non-inductive path to ground through a dielectric, of a plurality of resonating circuits which respond to high frequency oscillations, auxiliary electrodes having differing inductances in series therewith connected to the conductor and co-operating through spark gaps with the main electrode to ionize said dielectric and thereby establish a conducting path to ground through said main electrode.

7. In a protective device for electric conductors, the combination with a main electrode connected to the conductor and forming a discharge path to ground through a main spark gap, of a plurality of resonating circuits each comprising, an auxiliary electrode connected to the conductor through differing amounts of inductance, and co-operating with the main electrode through a spark gap of different length but each shorter than said main spark gap.

In witness whereof, I have hereunto set my hand this 12th day of July, 1907.

ELMER E. F. CREIGHTON.
